UNITED STATES PATENT OFFICE.

HENRY TOPHAM, OF PHILADELPHIA, PENNSYLVANIA, ASSIGNOR TO SCHIEPPERS BROTHIERS, OF SAME PLACE.

DESIGN FOR FABRIC FOR CLOAKING, &c.

SPECIFICATION forming part of Design No. 19,073, dated April 30, 1889.

Application filed March 27, 1889. Serial No. 305,003. Term of patent 3½ years.

To all whom it may concern:

Be it known that I, HENRY TOPHAM, a citizen of the United States, residing at the city of Philadelphia, in the county of Philadelphia and State of Pennsylvania, have invented and produced a new and original Design for Fabric for Cloaking, &c., of which the following is a specification, reference being had to the accompanying photograph, forming part hereof, in which is illustrated in front elevation the design for fabric for cloaking, &c., embodying the characteristic features of my invention.

The leading features of my design consist, broadly, of irregular or fanciful configurations disposed in wide broken stripes having waving and curvilinear contours, which are alternated with narrow stripes of differently-disposed fanciful configurations having waving or zigzag contours, and both of the said stripes running the entire length of the goods, as hereinafter more particularly described.

Referring to the accompanying photograph, forming part hereof, A represents the wide broken stripes, composed of either solid or broken bars or blocks B, indiscriminately disposed and forming different configurations. Each of the blocks or bars B is composed of slanting or parallel full or dotted lines in 30 white or other preferred color. The broken dotted bars C and the full-line bar B lie parallel, or substantially so, to each other and the ends of the goods, thereby presenting to the eye a wide broken stripe running the entire length thereof in curvilinear or waving outlines and forming several irregular and fanciful configurations.

The different configurations embodying the features of my invention are repeated alternately through the broad or wide stripe, while those between the alternate configurations are disposed in an inverse manner.

Starting now from the top of the configuration or design, it consists, first, of a fanciful letter "y," designated in the photograph by the letter f, and beneath which, in contact with its first stroke, is a transversely-disposed fanciful-shaped figure "2," which is designated by the letter g, and whose base is parallel with the left-hand edge of the goods. The base is somewhat broadened toward the termination thereof. Beneath the fanciful

figure "2," and in contact with the upper curved portion thereof, is a conventional three-leaf clover or three-pointed star (designated by h) within the field of the stripe and opposite the broadened base of the figure "2." To the left of the said conventional three-leaf clover or three-pointed star h is a crescent or new moon, i.

The configurations just described constituting the design are then repeated inversely, so that the base of the figure "2" is parallel, or substantially so, with the right-hand edge of the goods, while the other fanciful figures or conventional characters assume their relative positions to the figure "2."

K represents the narrow stripe, consisting of slanting or parallel rows of fine dotted or full lines, forming blocks or bars l, which bars or blocks are substantially parallel with the sides of the goods. The bars or blocks l are of different lengths, some of which are broken, and the whole thereby presenting to the eye a narrow stripe of curvilinear contour running the entire length of the goods parallel with the wide stripe hereinbefore described.

Starting now from the top of one of the configurations of the narrow stripe, it consists, first, of an inverted interrogation-mark ?, designated by m, and having a bar, n, across the end thereof. Beneath this interrogation-point ?, and in contact with the lower portion thereof, is a letter "s," designated by the letter o, and beneath the same, and in contact with the lower curve of the "s," is an inverted letter "g," designated by p.

The above-mentioned configurations constituting the design of the narrow stripe are repeated throughout the length of the stripes.

Having thus described the nature and objects of my invention, what I claim as new, and desire to secure by Letters Patent, is—

The design for fabric for cloaking, &c., as herein described, and shown in the accompanying illustration.

In witness whereof I have hereunto set my signature in the presence of two subscribing witnesses.

HENRY TOPHAM.
